UNITED STATES PATENT OFFICE.

WILLIAM A. MITCHELL, OF DENISON, TEXAS.

STEP.

Application filed January 30, 1922. Serial No. 532,709.

To all whom it may concern:

Be it known that I, WILLIAM A. MITCHELL, a citizen of the United States, residing at Denison, in the county of Grayson and State 5 of Texas, have invented a certain new and useful Improvement in Steps, of which the following is a full, clear, concise, and exact description, reference being had to the accompanying drawings, forming a part of 10 this specification.

This invention relates to improvements in steps.

The object of the invention is to provide a durable, strong and safe step or stairs particularly adapted for application to railway 15 passenger equipment.

In the drawing forming a part of this specification, Figure 1 is a vertical, sectional view of a car step showing my improvements 20 in connection therewith. Figure 2 is a top plan view, upon an enlarged scale, of one of the treads employed in the step. And Figure 3 is a transverse, sectional view corresponding substantially to the line 3--3 of 25 Figure 2 and on a somewhat larger scale.

In said drawing, one of the stair stringers is indicated at 10, the same being of suitable shape and preferably of sheet metal and with the outer exposed edge covered by a 30 strip 11. The step or stairway as shown is provided with four treads, each indicated broadly by the reference character A. Three risers B are employed for the three upper treads. Each of the risers B is preferably 35 in the form of a strip of sheet metal presenting a vertical main web 12 and top and bottom inwardly extended flanges 13--13. At each end, preferably integral right-angled flanges 14 are also provided to facilitate 40 attachment of the riser to the stringers as by rivets.

Each of the treads is of improved form, the details of which are best shown in Figures 2 and 3. Each tread A, as shown, comprises a sheet metal member having a bottom horizontal main portion 15, upwardly extending front and rear integral flanges 45 16--16, and top inwardly and horizontally extended narrow edges 17--17 overhanging 50 the bottom section 15. It will be noted that the flanges 16 and the bottom main web 15 are provided with a relatively large number of holes or openings 18--18, the purpose of 55 which is explained hereinafter. Within the pan-shaped sheet metal member above described and extending lengthwise thereof

preferably at the center, is a combined reinforcing and anchoring element as indicated at C. Said element C, as shown, is of more or less U-cross section having a bottom web 60 19 seated upon and riveted to the horizontal bottom portion 15, upstanding side arms 20--20, the latter having their top portions outwardly and horizontally extended as indicated at 21--21 so that the latter overlie 65 but are spaced from the bottom portion 15.

The pan-shaped member with its anchoring element C is filled with any suitable material adapted to assume a plastic form and which may be poured therein while in plastic condition and thereafter allowed to set. Said filling, indicated at 22 may be of suitable composition especially adapted to resist wear. Preferably the top surface of the filling will be left slightly above the top surfaces of the inturned edges 17, as best shown in Figure 3.

By employing the anchoring element C, it will be noted that the plastic material will be caught under the flanges 21 and thereby 80 securely anchored to the pan-shaped tread member. Furthermore, the plastic filling will be caught under the inturned edges 17--17 and within the anchoring openings 18 which are distributed throughout the 85 pan-shaped tread member. Said openings 18, in addition to performing the anchorage function above mentioned, serve another important function in that they permit of air and any moisture which may be trapped 90 within the plastic composition during the pouring thereof, to get out through said openings. Furthermore, in the event water seeps into or around the plastic material and tends to expand or freeze in cold weather, 95 the said openings 18 permit the trapped water to pass out and also the plastic material to expand sufficiently to prevent distortion of the sheet metal pan-shaped tread element. With this arrangement, the tread 100 member of my improvements has long life and retains its essential characteristics of strength and safety.

The treads are adapted to be secured to the stringers in any suitable manner, as for instance by angle iron brackets 23 at each end 105 of the tread.

I have herein shown and described what I now consider the preferred manner of carrying out the invention, but the same is 110 merely illustrative, and all changes and modifications are contemplated that come

within the scope of the claims appended hereto.

I claim:

1. A tread for stairs comprising, a pan-shaped sheet metal member having a horizontal bottom portion and upwardly extended front and rear flanges; a relatively shallow anchoring element secured to said horizontal bottom portion on the interior of said member, said element having portions overlying and spaced from said bottom portion; and a filling of plastic material within said member and partially extended beneath said portions of said anchoring element.
2. A tread for stairs comprising, a pan-shaped sheet metal member having a horizontal bottom portion and upwardly extended front and rear flanges; of a combined reinforcing and anchoring element secured to said member, said element being of substantially U-cross section with the side arms thereof extended outwardly approximately parallel to said bottom portion; and a filling of plastic material within said member having portions thereof beneath said flanges of the anchoring element.
3. A tread for stairs comprising, a pan-shaped sheet metal member having a horizontal bottom portion, front and rear flanges, the latter having their upper edges turned inwardly and over the bottom portion, said sheet metal member being provided with a plurality of combined ventilating and an-

choring openings; a longitudinally extending anchoring element secured to said horizontal bottom portion and having flanges above and spaced from said bottom portion; and a filling of plastic material within said member having portions thereof beneath said flanges of the anchoring element and portions extended within said openings.

4. A tread for stairs comprising, a pan-shaped metal member having a horizontal bottom portion and upwardly extended front and rear flanges, the latter having their upper edges turned oppositely inwardly, said bottom and said edge portions having a plurality of combined ventilating and anchoring openings therein; of a combined reinforcing and anchoring element on the interior of said member extending lengthwise thereof and secured to the bottom portion, said anchoring element being of substantially U-shape with the sides thereof outwardly flared; and a filling of plastic material anchored beneath said element and having portions thereof anchored also within said openings.

In witness that I claim the foregoing I have hereunto subscribed my name this 16 day of Jan., 1922.

WILLIAM A. MITCHELL.
